JOHANNES KARL RUTHS, OF DJURSHOLM, SWEDEN, ASSIGNOR TO AKTIEBOLAGET VAPORACKUMULATOR, OF STOCKHOLM, SWEDEN, A CORPORATION.

PRESSURE LOCK FOR DIGESTERS.

1,419,763.

Specification of Letters Patent. Patented June 13, 1922.

Application filed December 4, 1919. Serial No. 342,474.

To all whom it may concern:

Be it known that I, JOHANNES KARL RUTHS, Dr.-engineer, subject of the King of Sweden, residing at Djursholm, in the Kingdom of Sweden, have invented certain new and useful Improvements in Pressure Locks for Digesters, of which the following is a specification.

When carrying out digesting processes, 10 for instance in boiling wood splinters in sulphite boilers, it often happens that the pressure of the steam conduit sinks below the pressure prevailing in the digester, so that part of the acid may be forced back into the 15 steam conduit. This may for instance be the case where steam is taken in great quantities to be used for steaming purposes, or to start another digester. It may also happen that the valve in the steam pipe immediately before the digester is untight, or 20 that it stands open for the time being, thus causing acid to flow back at a direct boiling. In indirect boiling, the tubes or tube coils may be untight so that acid can flow 25 into the conduit.

Lye or acid finding its way into the piping system in the manner described will in such plants often give rise to great difficulties and drawbacks, the acid corroding the pipes 30 and often getting even into the boilers, or into an accumulator, steam turbine or the like which may be connected to the piping. Obviously, the various apparatus are in such cases subject to serious break-downs; in 35 many cases endeavours have been made to protect the pipes by making same of acid-proof material in spite of the high costs, as far as this has been possible. In certain other cases endeavours have been made to 40 overcome the drawbacks by arranging apparatus in the conduits to give a signal at the moment when acid entered the piping, so that the latter could then be shut off.

The present invention has for its purpose 45 to obviate these inconveniences by means fully protecting the apparatus connected to the pipings, or the pipings themselves, against corrosion by the action of escaping acid, without any particular signalling devices having to be resorted to. At the same 50 time the great advantage is obtained that the valves of the conduit are kept entirely free from acid, whereby the durability of the valves is greatly increased, and the maintenance expenditures correspondingly lowered.

As a proof of the real extent of the danger encountered with in the said respect it may be mentioned that in indirect boiling the heating of the contents of the digester was never attempted at a steam pressure 60 lower than the pressure prevailing in the boiler in spite of the fact that a number of advantages could be attained by such a proceeding. The case is namely such that the pressure in the digester rises considerably 65 faster, owing to the gases developed, than corresponding to the temperature of the contents of the digester, and therefore the starting of the digester up to 100° C. for instance in sulphite boiling could be easily effected 70 at a lower pressure, for example 1 kilogramme overpressure, but for the risk of getting acid into the piping through untight boiling tubes. By the present invention this part of the boiling process is facilitated 75 so that it can be carried out at a considerably lower pressure, which evidently is of particular importance where counter pressure power is to be generated in the boiling steam.

Likewise, by the use of the present invention, the steaming in a sulphite boiling plant may be effected at a pressure but a little exceeding the atmospheric pressure, and hereby certain advantages will also be attained.

The invention is characterized by the arrangement of a pressure lock in the steam piping near the digester, immediately beside the acid-proof cut-off valve, the said pressure lock consisting of a short piece of acid-proof piping, behind which is disposed a valve, preferably a non-return valve opening towards the digester. Between these two valves, preferably as closely as possible to the latter one, a pressure medium, such as 90 steam, water under pressure, air or the like is introduced into the piping, the said medium always having a pressure exceeding the maximum pressure of the digester. Preferably, steam is used for this purpose, and the maximum quantity of steam flowing to the place in question is checked by a small valve, a pressure flange or the like, and selected so large as to surely exceed that quantity of steam, which were likely to flow out in case of a leakage occurring in the non-return valve or the acid-proof valve respectively. In most cases it will be found suitable also to arrange the acid-proof piping 95 between the two valves in the form of a liq- 105 uide.

uid seal, preferably in such manner that the part most remote from the digester is bent upwardly.

In certain cases it may happen that steam 5 of higher pressure than the maximum pressure of the digester is not always available. This is for instance the case where the boiler pressure exceeds the pressure of the digester only a little. In such cases it often happens 10 that in starting or steaming a digester, the pressure of the boilers will sink below the pressure prevailing in one or other of the digesters whereby acid may be forced back into the piping. In such cases there is arranged 15 according to the invention a smaller, insulated receptacle which is to the most part thereof filled with water, and into which steam is introduced from the boilers through a non-return valve opening towards the receptacle. Practically the receptacle has thus 20 always a steam pressure corresponding to the maximum boiler pressure, and is discharged only very slowly through that small quantity of steam which is apt to leak out 25 through the pressure lock.

This receptacle thus represents a steam accumulator from the top portion of which steam is taken to the pressure lock or the locks respectively.

30 The invention is illustrated in the accompanying drawing, Fig. 1 showing the pressure lock, and Fig. 2 the accumulator.

In Fig. 1, K denotes the digester, S the acid-proof lining, A the acid-proof cut-off 35 valve, T the pressure lock, and B the non-return valve which is connected to the steam piping L. V is a permanently adjusted valve in the narrow steam pipe M, in which always prevails a higher pressure. The 40 cut-off valve A and the pressure block T are, as mentioned above, made of acid-proof metal, whereas the valve V, the pipings L and M as well as the non-return valve B can be made of metal which is not acid-proof. From the valve A steam may flow 45 either directly into the digester, as indicated in Fig. 1, or the said digester may be connected with heat coils by means of which the contents of the digester is heated.

50 The operation of the plant is as follows:—

Assuming that the valves A and B are perfectly tight and closed for the time being, then the same steam pressure prevails in the pressure lock T as in the piping M. 55 If the valve A is now opened, this steam pressure will soon be equalized, and in the course of the boiling process a small quantity of steam will flow all the time from the pipe M together with the large quantity of steam through L into the boiler K. Supposing now that during this process 60 the steam pressure in the pipe L sinks below the pressure prevailing for the moment in the digester, acid will immediately force 65 its way from the digester through the valve

A and into the pressure lock T, the non-return valve B being then closed, and now the steam flowing through the pipe M prevents the acid from rising in the pressure lock T. The quantity of steam flowing forth 70 from the conduit M will by degrees force the acid back from the pressure lock T, until the acid has settled along the line H—H. Thus it will be understood that the valve B or pipings or apparatus located in 75 front of it never come in contact with the acid. Conditions will be the same should the valve A not be perfectly tight.

In most cases the conduit M is led from the steam boiler. Should, however, the 80 boiler pressure not exceed the maximum pressure requisite for the boiling by a considerable amount, or should it, indeed, sometimes sink below this pressure, the pressure medium has to be taken from another pressure receptacle. If it is then desired to 85 employ steam as a pressure medium, the arrangement shown in Fig. 2 may be used to advantage.

P is the boiler battery which is built for 90 instance for a pressure of 6 kilogrammes, whereas the digesters K₁ and K₂ are started for example to a maximum pressure of 5.5 kilogrammes. It is now supposed that the digester K₂ for the time being is steamed 95 through the piping L₂, while the digester K₁ is boiling through the piping L₁, and that the pressure of the latter digester is for the moment just 5.5 kilogrammes. By the steaming the pressure in the boiler piping 100 L_p may sink for instance to 4 kilogrammes, and there is danger in the possibility of acid finding its way from the digester K₁ through the piping L₁ into the boilers. This is avoided by a pressure lock according to 105 Fig. 1, which is supplied with steam from an accumulator X filled with water, the said accumulator communicating with the boiler piping L_p through the non-return valve Y and the piping Z. If found suitable, a valve Q may be arranged in the piping Z. Thus the pressure lock or locks 110 respectively communicate with the steam space of the accumulator, while the water space thereof communicates with the boilers. Hereby the accumulator is always 115 kept charged to a pressure approaching the maximum pressure of the boilers.

What I claim as new and desire to secure by Letters Patent of the United States is:— 120

1. In digesters, the combination with the steam boiler, a steam conduit, a cut-off valve and another valve, of a pressure lock consisting of a pipe opening into the said steam conduit between the said cut-off valve 125 and the said other valve, the said pipe communicating with a pressure medium of higher pressure than the maximum pressure of the digester.

2. In a construction as specified in claim 130

- 1, the arrangement of the said pipe opening into the said steam conduit between the cut-off valve and a non-return valve.
3. In a construction as specified in claim 5 1, the arrangement of the said pipe communicating with steam of higher pressure than the maximum pressure of the digester.
4. In a construction as specified in claim 1, the arrangement of a connecting pipe 10 between the said two valves, the said connecting pipe being vertically arranged for the purpose of producing a liquid seal.
5. In a construction as specified in claim

1, the arrangement of a steam accumulator, and a non-return valve in the connection 15 between said steam accumulator and the steam boiler, the pipe to the pressure-lock extending from the said steam accumulator.

In testimony whereof I affix my signature in presence of two witnesses.

JOHANNES KARL RUTHS.
